DESIGN FOR A SPRAY NOZZLE

John O. Lewis, New York, N. Y.

Application February 7, 1942, Serial No. 105,705

Term of patent 14 years

To all whom it may concern:

Be it known that I, John O. Lewis, a citizen of the United States and a resident of the city of New York, county of Queens, and State of New York, have invented a certain new, original, and ornamental Design for a Spray Nozzle, of which the following is a specification, reference being had to the accompanying drawing forming a part hereof, in which

Figure 1 is a top plan view of a spray nozzle showing my new design; Figure 2 is a side elevational view of the same; and Figure 3 is a view of the bottom or underside of the nozzle.

I claim:

The ornamental design for a Spray nozzle, substantially as shown.

JOHN O. LEWIS.
